(74) Attorney, Agent, or Firm — Lavery, de Billy, L.L.P.;
Gonzalo Lavin(57) **CLAIM**

The ornamental design for a ladder safety device, as shown and described.

DESCRIPTION

FIG. 1 is a perspective front view of a ladder safety device showing our new design;

FIG. 2 is a top plan view thereof;

FIG. 3 is a right elevational view thereof;

FIG. 4 is a left elevational view thereof;

FIG. 5 is a front elevational view thereof;

FIG. 6 is a rear elevational plan view thereof; and,

FIG. 7 is a bottom plan view thereof.
